EYELASH CURLER

Harold Wasserman, New Haven, Conn.

Application December 29, 1944, Serial No. 570,242

5 Claims. (Cl. 132—32)

This invention relates to new and useful improvements in an eye-lash curler.

More specifically, the present invention proposes the construction of any eye-lash curler characterized by having a stationary member provided with an eye-lash curling element, and a movable member provided with a corresponding eye-lash curling element, the stationary member being formed of a plurality of parts constructed in a manner enabling easy manufacture of the curler and assemblage of the various parts, particularly of the movable member with the stationary member.

A further object is to provide a curler as aforesaid, in which the movable member is telescoped inside of the stationary member.

Another object is to provide a curler as aforesaid, in which the parts of the stationary member are connected by dowels.

Still another object is to provide the stationary member with a dependable guide way insuring accurate coaction of the two curling elements.

A further object is to provide a curler as aforesaid having a movable member provided with a shoulder and a flexible insert therein.

Another object is to provide a curler as aforesaid having a movable member provided with a flexible pad cemented thereto.

Another object is to provide a curler as aforesaid having a movable member provided with a flexible pad secured thereto by a dovetail connection.

For further comprehension of the invention, and of the objects and advantages thereof, reference will be had to the following description and accompanying drawings, and to the appended claims, in which the various novel features of the invention are more particularly set forth.

In the accompanying drawings forming a material part of this disclosure:

Fig. 1 is a perspective view of an eye-lash curler constructed in accordance with this invention.

Fig. 2 is a central axial section of the curler, parts being shown in full.

Fig. 3 is a central axial section of the stationary member of the curler, the parts thereof being disposed in spaced relation.

Fig. 4 is a side elevation of the movable member of the curler.

Fig. 5 is a plan view of the middle part of the stationary member.

Fig. 6 is a plan view of the bottom part of the stationary member.

Fig. 7 is a plan view of the movable member.

Fig. 8 is a similar view of Fig. 7 but showing a modified form of the invention.

Fig. 9 is a view similar to Fig. 7 but showing a further modification of the invention.

Fig. 10 is an enlarged section on the line 10—10 of Fig. 9.

Fig. 11 is a view similar to Fig. 7 but showing a further modification of the invention.

Fig. 12 is an enlarged section on the line 12—12 of Fig. 11.

Fig. 13 is a view similar to Fig. 7 but showing a further modification of the invention.

Fig. 14 is an enlarged section on the line 14—14 of Fig. 13.

The eye-lash curler, according to this invention, comprises a stationary member 10 and a movable member 11. The movable member 11 includes a long cylindrical stem 12 having an orifice 13 at its lower end and two diverging arms 14 at its upper end, the free ends at which support and are connected to a rigid eye-lash curling element 15. Element 15 is curved similar to the shape of a normal eye-lash and is adapted, in use, to engage the under surface of eye-lashes of an eye. The arms, besides diverging, are also curved somewhat and position the element 15 outwardly from the stem a sufficient distance so that the stem may be disposed vertically in line with a person's face and the element 15 will extend toward the face sufficiently to engage the eye-lashes.

The movable member 11 further includes a guide 16 which is substantially rectangular as to three of its sides. Guide 16 is directly above and integral with the stem 12. Element 15 is channeled to provide a curved groove 17 for a purpose presently to appear.

The stationary member 10 is formed of three parts, a top part 18, a middle part or sleeve 19 and a bottom part or sleeve 20. Sleeve 20 has a large diameter central bore 21 threaded at its lower end. The sleeve 20 is rectangular in cross section. Its upper face is provided with four recesses 22 equally spaced about the bore 21, one in each of the four corners of the upper face.

Sleeve 19 has a central bore, the lower portion 23 being of the same diameter as the bore 21 and the upper portion 24 being of smaller diameter providing a shoulder 25. Four dowels 26 depend from the lower face of the sleeve 19 and are tightly pressed into the recesses 22, connecting sleeve 19 to sleeve 20 but permitting them to be pulled apart when desired. A flange 21 surrounds the lower edge of the sleeve 19.

Sleeve 19 has an upper face 28 extending partly across its width, and therebelow another face 29 extending across the remainder of its width. Bore portion 24 opens through face 29. A three-sided rectangular guide-way 30 is formed in the upper face 28 and extends to the lower face 29, providing a vertical track for guide 16, which is disposed therein when the movable member is associated with the stationary member. Upper face 28 is provided with four recesses 31, two on one side and two on the opposite side of the guide-way 30.

Top part 18 has rectangular base 32 in line with the top face 29 and provided with four dowels 33 which depend from the bottom of the base into recesses 31, into which they are tightly pressed, holding the top part to the top sleeve, but permitting them to be pulled apart when desired. Two diverging arms 34 extend from the base 32 over and similarly to the arms 14, and these arms 34 support and are connected to a curved eyelash curling element 35 which is blade-like in formation and is positioned to coact with the groove 17 of element 15 when element 15 is moved into engagement with element 35, as will presently appear.

In assembling the movable member with the stationary member, the stem 12 of the movable member is first placed in the bores of the sleeve 19, with the guide 16 disposed in the guide-way 30. Then a coil spring 36 is slipped over the lower end of the stem 12 depending from the sleeve 19, the top of the spring 36 engaging the shoulder 25. The spring is then compressed somewhat and a pin 37 slipped through orifice 13, forming a bottom seat for the spring. Top part 18 is then assembled with the top sleeve, its dowels being pressed into the recesses 31. Then the lower sleeve 20 is slid over the lower end of the stem 12, housing the coil spring and being secured to the sleeve 19 by the dowels 26. Lastly, a hollow nut 38 is slid over the lower end of the stem and threaded into the bottom of the bore 21.

It will be seen from the foregoing description that the parts are so constructed that they can be easily made, and easily assembled. By making the top curling element supporting part separate from the top sleeve, the movable member can easily be telescoped with the stationary member. By making the bottom sleeve separate from the top sleeve, the spring can be easily assembled on the stem and the pin can be inserted. After the bottom sleeve is secured to the top sleeve, the bottom sleeve acts as a retainer for the pin 13, which could not be inserted if the bottom sleeve were connected to the top sleeve first.

The operation of the eye-lash curler is as follows:

The coil spring 36 normally holds the eye-lash curling elements 15 and 35 apart. The person using the curler places the thumb of his right hand under the stem 12 and the sleeve 19 above the flange 27 between the index finger and the next finger of his right hand. The flange prevents the sleeve from slipping through his fingers when he exerts pressure with his thumb. The thumb pressure moves the element 15 toward the element 35. If element 35 is positioned in contact with the upper surfaces of the eye lashes of one eye at the base of the eye lashes, the element 15 will rise to meet the lower surfaces of these eye lashes. The eye lashes will then be pressed against the element 35 by the groove 17, the

groove 17 causing the eye lashes to curl upwardly in an attractive way. A slight pressure between the elements will put a curl in the eye lashes which will remain when the curler is removed. If desired, the groove 17 may contain a small deposit of wax or other cosmetic which will "wax" and thus make permanent the curl given to the eye lashes. When the stem 12 is released, the coil spring will separate and release the eye lashes.

It is an important feature of the present invention that while the curler is of small dimensions, nevertheless a very reliable guide for the elements is provided which will insure a correct meeting of the elements. It is obvious that should one of the members be able to turn slightly relative to the other of the members, the curling elements, being out on the ends of the long arms, would get far out of alignment, and thus could not perform their intended duties. The relatively large guide 16 working in the relatively large guide-way 30, and the rectangular shape of guide and guide-way, insure that no rotation will occur between the two members. This guide and guide-way construction is believed to be far superior to other guide-way constructions that have been employed in eye lash curlers, such other guide-way constructions usually being frail and because of the small size of the eye lash curler, usually soon become so loose as to fail to hold the curling elements in the necessary exact alignment.

In Fig. 8 the eye lash curling element 15' is shown to be supported by a single arm 14'. In other respects this form of the invention is similar to that previously shown and like reference numerals identify like parts in each of the several views.

Three modified forms of movable members are shown in Figs. 9-14. These movable members may be used in place of the movable member 11, and like references will indicate like parts with appropriate accents added.

The movable member 11" of Figs. 9-10 has a shoulder 40 provided with a horizontal leg 41 and a vertical leg 42. A flexible pad 43 is disposed in the shoulder and secured thereto by pins 44.

The movable member 11"" of Figs. 11-12 has a flat face 45 to which a flexible pad 43' is secured by a layer of cement 46.

The movable member 11'"" of Figs. 13-14 has a dovetail tongue 47 on which is secured a flexible pad 43" having a dove-tail groove 48.

The flexible pads 43, 43' and 43" may be made of felt, rubber or other suitable material. They are each adapted to be engaged and slightly impressed by the element 35 of the stationary member. Each of the pads is curved similarly to the element 35. When the eye-lashes are squeezed between the element 35 and either of the three pads, the lashes are curled and pressed tightly into the pad so that the pad makes the curl permanent.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. An eye lash curler comprising relatively movable telescoped members, the outer of said members including two connected sleeves, one having a large diameter bore and the other hav-

ing a large diameter bore adjacent said first mentioned bore, and a small diameter bore therebeyond forming a shoulder, said small diameter bore opening through a face of said other sleeve, said other sleeve having another face substantially parallel to said first mentioned face and spaced therefrom, a guideway parallel to the axes of said bores extending between said faces, the inner of said members being slidably mounted in said bores and having a guide sliding in said guideway, said outer member further including a part connected to said other face and having a curved curling element, said inner member having a curved curling element in line with said first mentioned element and adapted to engage same by said relative movement, a coil spring surrounding said inner member and being disposed in said large bores, one end of said spring seating against said shoulder, said inner member having an orifice in said first mentioned sleeve bore and a pin in said orifice forming a seat for the other end of said spring.

2. An eye lash curler comprising two relatively movable telescoped members, the outer of said member including two sleeves removably connected by dowels, one having a large diameter bore and the other having a large diameter bore adjacent said first mentioned bore, and a small diameter bore therebeyond forming a shoulder, said small diameter bore opening through a face of said other sleeve, said other sleeve having another face substantially parallel to said first mentioned face and spaced therefrom, a guideway parallel to the axes of said bores extending between said faces, the inner of said members being slidably mounted in said bores and having a guide sliding in said guideway, said outer member further including a part removably connected by dowels to said other face and having a curved curling element, said inner member having a curved curling element in line with said first mentioned element and adapted to engage same by said relative movement, a coil spring surrounding said inner member and being disposed in said large bores, one end of said spring seating against said shoulder, said inner member having an orifice in said first mentioned sleeve bore and a pin in said orifice forming a seat for the other end of said spring.

3. An eyelash curler comprising two relatively movable telescoped members, the outer of said member including two sleeves removably connected by dowels, one having a large diameter bore and the other having a large diameter bore adjacent said first mentioned bore, and a small diameter bore therebeyond forming a shoulder, said small diameter bore opening through a face of said other sleeve, said other sleeve having another face substantially parallel to said first mentioned face and spaced therefrom, a guideway parallel to the axes of said bores extending between said faces, the inner of said members being slidably mounted in said bores and having a guide sliding in said guideway, said outer member further including a part removably connected by dowels to said other face and having a curved curling element, said inner member having a

curved curling element in line with said first mentioned element and adapted to engage same by said relative movement, a coil spring surrounding said inner member and being disposed in said

5 large bores, one end of said spring seating against said shoulder, said inner member having an orifice in said first mentioned sleeve bore and a pin in said orifice forming a seat for the other end of said spring, and a hollow nut screwed in threads in the ends of said first mentioned sleeve remote from said other sleeve, said inner member slidably passing through and being guided by said nut.

4. An eye lash curler comprising two relatively movable telescoped members, the outer of said members including two connected sleeves, one having a large diameter bore and the other having a large diameter bore adjacent said first mentioned bore, a small diameter bore therebeyond forming a shoulder, said small diameter bore opening through a face of said other sleeve, and an outer flange adjacent said first mentioned sleeve, said other sleeve having another face substantially parallel to said first mentioned face and spaced therefrom, a guideway parallel to the axes of said bores extending between said faces, the inner of said members being slidably mounted in said bores and having a guide sliding in said guideway, said outer member further including a part connected to said other face and having a curved curling element, said inner member having a curved curling element in line with said first mentioned element and adapted to engage same by said relative movement, a coil spring surrounding said inner member and being disposed in said large bores, one end of said spring seating against said shoulder, said inner member having an orifice in said first mentioned sleeve bore and a pin in said orifice forming a seat for the other end of said spring.

5. An eye lash curler comprising two relatively movable telescoped members, the outer of said members including two connected sleeves, one having a large diameter cylindrical bore and the other having a large diameter cylindrical bore adjacent said first mentioned bore, and a small diameter cylindrical bore therebeyond forming a shoulder, said small diameter bore opening through a face of said other sleeve, said other sleeve having another face substantially parallel to said first mentioned face and spaced therefrom, a rectangular guideway parallel to the axes of said bores extending between said faces, the inner of said members being slidably mounted in said bores and having rectangular guide sliding in said guideway, said outer member further including a part connected to said other face and having a curved curling element, said inner member having a curved curling element in line with said first mentioned element and adapted to engage same by said relative movement, a coil spring surrounding said inner member and being disposed in said large bores, one end of said spring seating against said shoulder, said inner member having an orifice in said first mentioned sleeve bore and a pin in said orifice forming a seat for the other end of said spring.

HAROLD WASSERMAN.
